PRINTING DEVICE

Wilmer H. Nau, Gates Mills, Ohio, assignor to
Addressograph-Multigraph Corporation, Wil-
mington, Del., a corporation of Delaware

Application July 18, 1946, Serial No. 684,411

1 Claim. (Cl. 101—57)

1 This invention relates to printing and like de-
vices of the character that are passed sequen-
tially through printing or other machines to
have operations performed thereon or under con-
trol thereof.

Printing devices of the nature to which this invention pertains, which are sometimes also known as printing and control devices, usually have type characters thereon from which an impression may be made onto sheets or the like when the devices are passed through a suitable printing machine. In the illustrated form of the invention such type characters are embossed on a flat metal plate that is releasably retained on one face of the carrier or frame of the printing device. In those instances where type characters are embossed on a metal plate as aforesaid, an impression is usually made from at least selected of such type characters onto a card that is also releasably retained on the aforesaid face of the frame of the device to facilitate handling of the printing device particularly in the filing thereof, such printing devices usually being stored in drawers or the like when not in use in printing machines.

Moreover, printing devices of the character to which this invention pertains are usually equipped with means effective to classify the printing devices and one manner in which this is accom-
plished is to removably secure one or more tabs along one edge of the frame of such a printing device in such a manner that at least a portion of such a tab projects beyond an edge of the printing device, one arrangement of this char-
acter being disclosed in the patent to Gollwitzer No. 2,049,436, patented August 4, 1936.

In some instances where resort is had to one or more tabs secured to a printing device in the manner described hereinabove, the means in the machine adapted to cooperate with such tabs which are effective, for example, to determine whether or not an impression is to be made from a particular printing device during passage thereof through a printing machine, the sensing device of such means in the machine being ar-
ranged to cooperate with the face of such a tab when the tab is disposed at a particular predeter-
mined position along one edge of a printing device. In some instances the sensing means are arranged to cooperate with the middle por-
tion of a tab of predetermined width, and in other instances tabs of less than such predeter-
mined width are employed so that, for example, the sensing means will cooperate with but one-
half of a tab of predetermined width whereby

2 tabs of a width equal to approximately one-half of the standard width of tabs may be utilized. Resort to such half tabs is advantageous since it doubles the number of positions along the edge of a printing device whereat one or more tabs may be arranged for cooperation with sensing means of the aforesaid character.

It has been found heretofore it is oftentimes ad-
vantageous to further increase the positions
10 along an edge of a printing device whereat means
such as tabs or the like may be afforded for co-
operation with sensing means of the aforesaid
character, and to this end it has been proposed
heretofore to utilize tabs of the above described
15 kind which may include one or more openings or
embossures formed at selected or predetermined
positions. In such circumstances sensing means
of the aforesaid character are arranged to co-
operate with such openings or embossures in the
20 tabs. Inasmuch as such embossures or openings
may be incorporated at selected of a plurality
of positions on the tabs, it follows that the num-
ber of positions with which sensing means of the
25 aforesaid character may cooperate is materially
increased. One example of tabs arranged in the
above described manner is disclosed in the patent
to Gollwitzer No. 1,930,799, patented October 17,
1933.

It has also been proposed heretofore to provide
30 perforations in the frames of the printing de-
vices for the purpose of classifying the same or
to afford representations of data, one arrange-
ment of this character being disclosed in the
35 patent to Gollwitzer No. 2,132,412, patented
October 11, 1938. My invention may be em-
bodied in a printing device having perforations
formed therein for the purpose of classifying the
40 same or to afford data representations. Yet an-
other example of a printing device including one
or more perforated areas that may be utilized
for the purposes of classification or for data rep-
resentations is that to which the copending ap-
45 plication of Carl J. Hueber, Ser. No. 596,991, filed
June 1, 1945, pertains and my invention may
also be utilized in such printing devices.

In any instance, where means are provided on
printing and control or like device to classify the
same or to afford data representations, it is im-
portant that such means be accurately oriented
50 in the printing machines in which the devices are
utilized so as to insure accurate cooperation of
the sensing means provided in the machine with
the means on each device that impart classifica-
tion thereto or which afford data representations.
Moreover, it is important that the printing de-

vices be firmly retained in a predetermined position in the printing machine when sensing means or the like are to cooperate therewith and to enable such desiderata to be realized in a novel and expeditious manner is a primary object of the present invention.

Yet another object of this invention is to so arrange a printing device of the aforesaid character that portions will be afforded therein that are adapted for cooperation with means in printing machines and the like in which the devices are utilized which will insure that the printing devices will be held in a predetermined position and against canting in the predetermined position in the printing machine or the like, and an object ancillary to the foregoing is to form at least two portions on a printing device of the aforesaid character so that, when means in the printing machine are engaged therewith, the printing device will be firmly and accurately retained in position in the printing machine.

Printing devices of the nature to which this invention pertains are usually advanced seriatim through printing and like machines in a step by step manner and it is advantageous to insure that the printing devices will be accurately disposed in at least selected of the at rest positions thereof in the course of the step by step advancing of the printing devices through a printing or like machine and to insure that printing devices will be accurately arrested in at least selected of such positions is yet another object of this invention, and an object ancillary to the foregoing is to so arrange a printing device of the aforesaid character that means in a printing machine or the like may cooperate with a formed portion thereof to initially arrest the printing device at least approximately in the desired position thereof and to so relate other means in the printing machine to the initial movement arresting means therein that such other means will cooperate with another formed part on a printing device of this invention to insure final and accurate positioning of the printing device at a selected and predetermined position in a printing machine.

In order that a printing device may be disposed accurately in a predetermined position in a printing machine of the aforesaid character I have found it advantageous to provide an arrangement in the printing machine of such nature that a portion of a printing device may be engaged therewith in such a manner as to enable relative movement between the printing device and the means engaged therewith and also to provide means which will be effective to move the printing device relative to the means engageable therewith so as to insure accurate positioning of the printing device in the printing and like machine and so to do in a novel and expeditious manner is yet another object of this invention.

Further objects of this invention are to associate with a printing device guideway in a printing or like machine, at at least selected of the positions whereat the printing devices are to come to rest in the guideway, an arrangement with which the printing devices may be engaged that will be of such nature as to facilitate relative movement between the arrangement and a printing device in the event such relative movement should be required to insure accurate positioning of the printing device in the at rest position thereof in the printing device guideway; to utilize accurately positioned rollers with which an edge of a printing device may be engaged when disposed in an at rest position thereof in the guide-

way in a printing machine through which the printing device is being advanced; to arrange a mechanism for cooperation with the edge of a printing device opposite that engaged with rollers or the like of the aforesaid character that will be of such nature as to initially arrest movement of the printing devices in the selected at rest position thereof and which will also function to accurately position the device in such at rest position; and to utilize a common member including accurately related parts for the purpose of initially arresting a printing device in an at rest position thereof and to accurately position such printing device in such at rest position thereof.

Other and further objects of the present invention will be apparent from the following description and claims and are illustrated in the accompanying drawings which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a fragmentary perspective view of a portion of a printing machine of the character through which printing devices of the nature to which this invention pertains are to be passed and wherein a printing device is shown as being accurately positioned in one of the at rest positions of the printing devices in such printing machine;

Fig. 2 is a vertical sectional view taken substantially on the line 2—2 on Fig. 1;

Fig. 3 is a fragmentary plan view, in which certain portions are broken away, of a printing device accurately disposed in an at rest position in a printing device guideway; and

Figs. 4 and 5 are views similar to Fig. 3 showing modified forms of my invention.

The printing machine which is fragmentarily illustrated in the accompanying drawings includes a magazine M into which the printing devices of the present invention are introduced when these are to be advanced seriatim and in a step by step manner through the printing machine. The manner in which such printing devices are advanced through the printing machine, which is fragmentarily illustrated in the accompanying drawings, is shown and described in the patent to Carl J. Hueber No. 2,359,850, patented October 10, 1944, to which reference may be made for a detailed description of the manner in which the printing devices are advanced through the printing machine.

In Fig. 1 I have illustrated an arrangement that is adapted for cooperation with tabs as T provided on the printing devices as D and the illustrated form of such arrangement is one which is effective to determine whether or not impressions are to be made from the printing devices when these devices move into printing position (not shown) in the machine that is fragmentarily illustrated in Fig. 1. An arrangement of this particular character is commonly referred to in the art as a selector mechanism, and the particular selector mechanism of which a portion is shown in Fig. 1 is of the character shown and described in the patent to Carl J. Hueber No. 2,359,851, patented October 10, 1944.

The sensing means SM of this selector mechanism is illustrated in Fig. 1, and the manner in which this sensing means is operated and the manner in which the selector of which this sensing means is a part functions may be readily ascertained by referring to said Hueber Patent No. 2,359,851. In order to facilitate reference to such patent, those reference characters of greater numerical significance than 100 which appear on the accompanying drawing are the same reference characters as those which are utilized in said Patent No. 2,359,851 to designate the parts shown in that patent which also appear in the accompanying drawings.

A typical printing device in which my invention may be incorporated is illustrated in plan in Fig. 3, this particular printing device being of the character to which the Gollwitzer Reissue Patent No. 22,249, patented January 12, 1943, pertains. This printing device, generally indicated by D, includes a substantially rectangular frame, generally indicated by F, and which is desirably formed from sheet metal to include spacing flanges as SF (Fig. 2) on the rear face and along the shorter edges thereof. A printing plate P is releasably retained on the front face of the frame F and type characters TC are embossed on this plate P. An index card C is also releasably retained on the front face of the frame F and desirably an impression is made from at least selected of the type characters TC onto this index card C so as to facilitate ascertainment of what may be printed from the type characters TC, since so to do facilitates handling of the printing device particularly in the filing thereof in a drawer or the like along with other printing devices of the nature to which this invention pertains.

When the printing devices D are introduced into the magazine M, they are withdrawn one by one from the bottom of a stack thereof in the magazine M and they first advance through a printing device guideway afforded between the girders or rails 151 and 152, retaining plates as 10 being effective to hold the printing devices down in the guideway. As explained in aforesaid Patent No. 2,359,851, carrier bars 153 are effective to advance the printing devices in a step by step manner through the printing device guideway, the manner in which carrier bars as 153 are effective to do this being described in full detail in said Patent No. 2,359,850. In the present instance, the printing devices as D are advanced from the magazine M into what is referred to as selector station I in said Patent No. 2,359,851, which is the position in which the printing device D is shown as being disposed in Fig. 1.

Tabs as T are secured in tab sockets as TS on the frame F as disclosed, for example, in the patent to Gollwitzer No. 2,049,436, patented August 4, 1936, so that the body of such a tab projects beyond what is the trailing edge of the printing device as it advances through the printing device guideway. When a printing device as D comes to rest in said station I, the tabs as T thereon are disposed above a tab supporting plate 510, which is in the nature of a comb, whereby the tabs may be aligned with sensing pins as 525C releasably retained at selected of predetermined positions in the sensing head (not shown) of the sensing means SM of the selector mechanism. As described in said Patent No. 2,359,851, the sensing pins as 525C are adapted to cooperate with perforations as 11 formed at selected of predetermined positions in the tabs as T. Subsequent to the time a printing device as D

comes to rest in station I, the pins as 525C are advanced towards perforations as 11 in tabs as T, and in those instances where a perforation as 11 is aligned with a pin as 525C, said pin passes through such perforation. When, however, an unperforated portion of a tab as T is aligned with a sensing pin as 525C and such pin engages such unperforated portion, the sensing head in which the pin is mounted is arrested in its movement so as to thereby be disposed in a position different from that in which this head would have been disposed had a pin as 525C passed through a perforation as 11. It will be appreciated that the perforations as 11 and the pins as 525C are of necessity of relatively restricted size wherefore it is important that the tabs as T and perforations as 11 therein be accurately positioned when a printing device as D is disposed in station I so as to insure accurate cooperation between the sensing pins as 525C and the perforations or lack of perforations as 11.

In order to insure that such accurate positioning of a printing device as D in a station as station I or any other station in the printing device 25 guideway through which the printing devices are advanced, I provide a substantially V-shaped notch as N in one of the shorter edges of the frame F of the printing device as D, such a notch desirably being located approximately midway between the longer edges of the substantially rectangular frame as F. In addition to providing a notch as N, I also cut away a corner of the frame as F at what will be the leading edge of a printing device as it passes through a printing device guideway in a printing or like machine 30 so as to thereby afford a horizontal shoulder S, and a vertical or longitudinal face SL. Desirably the notch as N and the shoulder as S are formed in the frame F of the printing device as D in the 35 course of fabrication thereof and desirably a single tool is employed to form the notch as N and the shoulder as S so as to thereby insure that this notch and shoulder will be accurately related one to the other in the frame of the printing device. Moreover, at the time the notch as N and 40 shoulder as S are formed in the frame F of a printing device, the frame is accurately located relative to the tool employed to form such notch and shoulder for so to do insures that the notch as N and shoulder as S will be accurately located 45 relative to the tab sockets as TS in which the tabs as T are to be mounted. Desirably tab sockets as TS and the tabs as T are of the nature disclosed in the above referred to Gollwitzer Patent No. 2,049,436, for resort for such an arrangement insures accurate positioning and accurate 50 retention of the tabs as T on the frame as F of a printing device as D. Therefore, the notch as N and the shoulder as S are accurately related one to the other and to the tab sockets as TS and 55 therefore to tabs as T to be mounted therein and consequently also to perforations as 11 in tabs as T.

Inasmuch as an accurate interrelation is established among the notch as N, the shoulder as S and tabs as T and perforations as 11 in tabs as T on a printing device as D, means may be provided in a printing machine which will be of such nature as to cooperate with a notch as N and a shoulder as S when a printing device as D is disposed at a predetermined position such as the station I in a printing machine. Moreover, the means in the machine that are to cooperate with a notch as N and shoulder as S may be 60 accurately related to means in the machine as the 65 70 75

pins 525C that are to cooperate with perforations as 11 in tabs as T on a printing device including the notch as N and the shoulder as S with which the aforesaid means in the machine are to cooperate at a particular time. Consequently, cooperation of the means in the machine with the notch as N, the shoulder as S and the longitudinal face as SL will be effective to insure that perforations as 11 will be accurately located relative to pins as 525C when a printing device is disposed in station I in those instances where the means adapted for cooperation with the notches as N, the shoulder as S and the longitudinal face as SL are provided at such station I.

In the present instance the means which are to cooperate with the notch as N and shoulder as S consist of a plate 12 which has ears as 13 and 14 at the lower ends thereof. The ears project inwardly from the main body of the plate and in the present instance these ears have rectangular openings as 15 formed therein to receive a rectangular bar as 16. The rectangular bar 16 has trunnions as 17 at opposite ends thereof which are rotatably mounted in brackets as 18 and 19 that are fast to the underside of the rail as 151 as best shown in Figs. 1 and 2.

A finger 20 projects inwardly from the main body of the plate 12 at the upper end thereof and includes a substantially V-shaped nose 21. Another finger 22 having a free end 24 projects inwardly from the upper edge of the plate 12, such finger 22 projecting inwardly of the apex of the V-shaped nose 21 to thereby provide a stop or horizontal edge 23 on the finger 22. The V-shaped nose 21 is formed to be complementary to the notch as N and the apex of the nose 21 is accurately spaced from the stop edge 23 in the same amount that the apex of the notch N is spaced from the shoulder S.

An arm 24 is fast to the bar 16 and is pivotally connected through a link 25 to a link 195 which in the manner explained in said Patent No. 2,359,851 is connected to one arm of a bellcrank that operates in timed relation with the means which are effective to reciprocate the carrier bars as 153 which advance the printing devices as D through the printing device guideway. The timed relation that is established between the operation of the carrier bars as 153 and the link as 195 is such that immediately prior to the time the carrier bars 153 reach the forward end of their advancing movement, to advance the printing device from the magazine M into station I, the link 195 is moved to the left as viewed in Fig. 2 to thereby rotate the bar 16 and therefore the plate 12 counterclockwise into the position in which the plate 12 is shown in Figs. 1 and 2.

The counterclockwise movement that is thus imparted to the plate 12 is effective first of all to dispose the stop edge 23 in position to engage the shoulder S when the printing device D on which the shoulder S is included attains the at rest position thereof in station I. Inasmuch as the stop edge 23 projects inwardly beyond the apex of the V-shaped nose 21, said stop edge engages the shoulder S prior to the time the nose 21 advances into the notch as N. When, however, the nose as 21 advances on to the notch as N, the complementary configurations of the notch as N and the nose 21 are effective to insure firm seating of the shoulder as S on the stop edge 23 and engagement between the free end 24 of finger 22 with the longitudinal face SL so that the printing device as D is accurately and firmly held in position against canting by the fitting

of the nose 21 in the notch as N, the engagement of the shoulder as S with the stop edge 23, and the engagement of the free end 24 of finger 22 with the longitudinal face SL at the leading corner of the printing device.

Inasmuch as a shoulder as S may not be fully engaged with the stop edge as 23 prior to the time the nose 21 enters the notch as N, it is advantageous to insure that relative movement between the nose as 21 and the walls of the notch as N may be effected, and to this end I provide rollers as 26 and 27 that are disposed in position to engage the edge of the frame as F of the printing device as D opposite the edge of such device in which the notch as N and the shoulder as S are formed, said rollers 26 and 27 being mounted in the top edge of the rail 152 in position to engage the adjacent edge of the frame F when a printing device as D is disposed in station I. The rollers 26 and 27 preferably include hardened peripheries and these rollers are accurately related one to the other and to the position in which it is desired to retain the printing device D in station I. Thus in the course of the aforesaid counterclockwise movement of the plate 12, the engagement of the nose as 21 and the free end 24 of the finger as 22 with a printing device as D at N and SL respectively is effective to force such printing device into engagement with the peripheries of the accurately positioned rollers 26 and 27, and this in cooperation with the accurate relation between the nose 21, stop edge 23, and the free end 24 of finger 22 and notch as N, shoulder as S, and the longitudinal face SL on the particular device insures accurate positioning of the printing device in station I. Furthermore, since the rollers as 26 and 27 are freely rotatable in the event that some relative movement occurs between the walls of the notch as N and the nose as 21, this may easily be effected by reason of the capability of the rollers 26 and 27 to freely rotate.

When the carrier bars as 153 are moved rearwardly to thereafter be again moved forwardly so as to advance the particular printing device as D which has been disposed in station I from this station and to advance another printing device from the magazine M into station I, the link 195 will operate to move the plate 12 clockwise, as viewed in Fig. 2, so as to thereby retract the nose 21 and stop edge 23 respectively from cooperation with the notch as N and shoulder as S, prior to the time the carrier bars as 153 start the forward advancing movement thereof to thereby free the printing device of station I from the retention thereof by the fingers 20 and 22.

In Fig. 4 I have shown a modified form of my invention and since in most respects the arrangement there illustrated corresponds to that described hereinabove, where an element appears in Fig. 4 that has been described hereinabove, the same reference character as that applied hereinabove to such element is employed in Fig. 4 except that the suffix "a" is added to the reference character where it appears in Fig. 4.

The printing device Da illustrated in Fig. 4 has a notch Na formed therein corresponding to the notch N in the printing device D shown in Figs. 1 to 3. However, a shoulder S and longitudinal face SL are not provided on the printing device Da, and in this device the notch Na is spaced away from what will be the leading edge of the printing device as it advances through a printing machine in such a way that an accurate relationship is established between this edge and the notch Na, just as an accurate relationship is

established between the notch N and the shoulder S in the printing device D shown in Figs. 1 to 3. A plate 12a is provided which functions like the plate 12 described hereinabove. The plate 12a has a finger 20a formed at the upper end thereof that includes a nose 21a which corresponds to the nose 21, said nose 21a being adapted to cooperate with the notch Na in the manner described hereinabove with reference to the nose 21 and notch N. The plate 12a also includes a finger 22a which has a notch 30 formed at the inner end thereof so as to thereby define a shoulder or horizontal stop edge 31 engageable with the leading end of the printing device at FE and a longitudinal face 32 engageable with the corresponding longitudinal face FL at the leading corner of the printing device.

When the plate 12a is moved toward the printing device Da, in the manner described hereinabove with reference to the plate 12, the shoulder 31 moves into position to engage the adjacent portion of the leading edge of a printing device moving into station Ia to thereby arrest advancing movement of printing device Da in station Ia, the shoulder 31 functioning in this instance like the stop edge 23 on the finger 22 and the longitudinal face 32 at the inner end of finger 22a functioning in this instance like the free end 24 of finger 22. Subsequent to the time the leading edge of a printing device has engaged the shoulder 31, the nose 21a advances into the notch Na, and since the shoulder 31 is accurately spaced from the apex of the nose 21a and since the notch Na is accurately spaced from the leading edge of the printing device Da, the engagement of such leading edge with the shoulder 31 and the seating of the nose 21a in the notch Na accurately orients the printing device in station Ia, the position of the printing device being accurately adjusted by the cooperation of the nose 21a with the notch Na and the cooperation of shoulder 31 and the longitudinal face 32 respectively with the leading end at FE and the longitudinal face FL of the printing device the rollers 26a and 27a functioning in this instance to facilitate adjustment of the position of the printing device as do the rollers 26 and 27 as described hereinabove.

A yet further modified form of my invention is shown in Fig. 5, and in this instance, where an element appears that has been described hereinabove, a reference character like that applied to such element in Figs. 1 to 3 is applied to the element where it appears in Fig. 5 but the suffix "b" is added to such reference character where it appears in Fig. 5.

The printing device Db shown in Fig. 5 does not have a notch as N or Na formed therein and this printing device is also not equipped with a shoulder as S. However, at the corner of the printing device where the shoulder S is formed in the printing device D shown in Fig. 3, the printing device Db is provided with a chamfered or bevelled edge 35. Moreover, the other corner of the printing device at the edge thereof in which the chamfered or bevelled edge 35 is provided is formed to embody a chamfered or bevelled edge 36. The bevelled edges 35 and 36 are accurately spaced one from the other in the manner in which the notch N and shoulder S are accurately spaced one from the other as hereinabove described.

Moreover, in this instance the plate 12b which functions in the manner described hereinabove with reference to the plate 12, is equipped with a finger 20b which, at the inner end thereof, is

provided with a chamfered or bevelled edge 33 that is complementary to and which is adapted to cooperate with the bevelled edge 36 on the printing device Db. The plate 12b also includes a finger 22b which is provided with a chamfered or bevelled edge 37 that is complementary to and which is adapted to cooperate with the bevelled edge 35. The bevelled edges 37 and 38 are accurately spaced one from the other as are the stop edge 23 and the apex of the nose 21 as described hereinabove. Therefore, when the edges 37 and 38 respectively move into cooperation with the edges 35 and 36, since the edges 37 and 38 are accurately spaced one from the other, and since the edges 35 and 36 are accurately spaced one from the other, and since the spacing between the edges 37 and 38 corresponds to the spacing between the edges 35 and 36, the printing device Db is accurately positioned in station Ib. In this instance by reason of the bevelled configuration of the cooperating edges as 35 and 37 and 36 and 38, the position of the printing device Db in station Ib may be adjusted to insure accurate orientation of the printing device Db in station Ib, and in this instance, the rollers 26b and 27b facilitate such movement of the printing device Db as may be necessary to insure accurate orientation thereof in station Ib, particularly if movement is effected as an incident to the edges 37 and 38 respectively moving into cooperation with the edges 35 and 36.

The edge 37 will serve as a stop edge and will be effective to arrest advancing movement of a printing device moving into station Ib just as the stop edge 23 is effective to arrest movement of a printing device moving into station I, Fig. 3. However, if the edge 35 does not remain in engagement with the edge 37, then as the edge 38 moves into cooperation with the edge 36, the position of the printing device will be adjusted in station Ib so that when the plate 12b has attained the inner position thereof, the printing device Db will be accurately oriented in station Ib.

It will be manifest from the foregoing description that by resort to arrangements such as are described hereinabove, a printing device may be accurately oriented in a predetermined position in a guideway for such devices provided in a printing or like machine, and it will therefore be seen that the hereinabove described arrangements enable the above set forth and kindred objects of this invention to be realized.

However, while I have illustrated and described preferred embodiments of my invention it is to be understood that these are capable of variation and modification and I therefore do not wish to be limited to the precise details set forth, but desire to avail myself of such changes and alterations as fall within the purview of the following claim.

I claim:

In a printing machine having spaced-apart first and second guide means determinative of a path of travel traced out by the first and second side edges of printing devices, which printing devices are progressively feedable along the guide means to a work-performing station in the machine whereat the printing devices are to be successively accurately positioned relative to detecting elements for cooperating with the printing devices, and which printing devices are each formed with a chamfered notch extending inwardly from a first point on the said first side edge removed a predetermined distance from a second point on the side edge extension of the

leading-most right-angled corner portion corresponding to the said first side edge, means at the work-performing station for locating and accurately positioning each of the printing devices relative to the detecting elements and comprising, a substantially U-shaped member positioned adjacent the outside of the first guide means and being operatively connected to the machine for reciprocation into and out of the so-defined path of travel in timed sequence relative to the feeding of the printing devices, the U-shaped member having first and second spaced-apart leg elements adapted to engage each of the printing devices at the said first and second points on the side edges thereof, the terminal free end of the first leg element being configured complementary to the said notch to thereby be seatable therein, the terminal free end of the second leg element being configured complementary to the said leading-most right-angled corner portion, the said terminal free ends having third and fourth points respectively alignable with and engageable with the said first and second points and the distance therebetween being equal to the distance between the said first and second points, the extent of reciprocation of the U-shaped member into the so-defined path of travel being such as to cause the said fourth point on the second leg

5

15

element to engage the said second point on the said first side edge and to cause the terminal free end of the first leg element to be seated in the said notch, and a pair of rollers at the work-performing station freely mounted for rotation in the second guide means, the peripheries of the rollers being located in position to be engaged by the second side edge of each of the printing devices when at the work-performing station whereby the terminal free ends of the leg elements and the freely rotatable rollers cooperate to accurately position the printing devices at the work-performing station.
